UNITED STATES PATENT OFFICE.

JESSE J. DILLON, OF COUNCIL BLUFFS, IOWA.

FLYING-MACHINE.

1,011,761.

Specification of Letters Patent. Patented Dec. 12, 1911.

Application filed March 25, 1911. Serial No. 616,803.

To all whom it may concern:

Be it known that I, JESSE J. DILLON, a citizen of the United States, residing at Council Bluffs, in the county of Pottawattamie and State of Iowa, have invented new and useful Improvements in Flying-Machines, of which the following is a specification.

This invention relates to flying machines 10 of the heavier-than-air type, and has for its objects the production of a machine employing rotary propellers of novel construction and operating as lifting and driving propellers and sustaining elements; to provide 15 an arrangement of parts whereby the center of gravity of the machine is placed at a low point, rendering the machine inherently stable; and to provide a novel construction and arrangement of parachute device which may 20 be thrown into operation to insure a safe descent when occasion requires.

The invention consists of the features of construction, combination and arrangement of parts, hereinafter fully described and 25 claimed, reference being had to the accompanying drawings, in which:—

Figure 1 is a front elevation of a flying machine embodying my invention. Fig. 2 is a side elevation of the same. Fig. 3 is 30 a sectional plan view on the line 3—3 of Fig. 1. Fig. 4 is a horizontal section through one of the propellers. Fig. 5 is a vertical transverse section through the upper portion of the machine, showing the 35 parachute folded. Fig. 6 is a similar view, showing the parachute unfolded for use.

Referring to the drawings, 1 designates a suspension tube or pipe carrying at its lower end a car or basket 2, to support the driving 40 motor, pilot, passengers, if any, and the controlling devices of the machine. Supported upon this suspension tube is a driving propeller 3 operative by suitable gearing from the motor 4. Projecting forward 45 wardly and rearwardly from the suspension tube at and above the car are front and rear frames or outriggers 5 and 6, preferably of substantially V-form, and cooperating to provide a suitably trussed triangular frame 50 structure carrying a front horizontal rudder 7 and a rear vertical rudder 8, which may be supported by suitable frame connections leading therefrom to the car or basket 2. The rudder 7 is preferably of the box-type, 55 having upper and lower curved surfaces, so that by adjustment its angle of inclination

may be changed to effect the ascent or descent of the machine.

Mounted upon the opposite sides of the frame structure 5 and 6 are vertical shafts 60 9 and 10 arranged in parallel relation to the upper end of the suspension tube and driven by suitable gearing from the motor. These shafts carry oppositely rotating lifting and sustaining wheels or propellers 11 65 and 12, each consisting of a frame structure carrying an annular series of lifters 13. Each of these lifters has approximately the form of a box kite, with its air passage facing in the direction of rotation, said lifter 70 being inclined at an angle to the horizontal, so that its upper and lower walls present the necessary angle of incidence for a supporting action upon the air. The said lifting propellers are rotated in opposite directions to maintain the lateral balance of the machine under ordinary conditions, so that the thrust of each propeller will oppose the 75 thrust of the other to prevent deflection of the machine from its prescribed course.

It will be understood that through the operation of the lifting propellers, the machine may be elevated to the desired altitude, and the speed of said propellers then slackened to adapt them to serve as sustaining elements, while the propeller 3 is employed to drive the machine forward. Upon reducing the speed of the lifting propellers below sustentation speed, it will, of course, 80 be understood that the machine may be allowed to descend at any rate of speed desired, thus enabling it to be safely controlled. By constructing the gearing in such manner as to drive the lifting propellers through 85 independent sets of gearing, said propellers may be driven at different rates of speed when desired, so that they may be employed for a lateral balancing action when necessary.

Extending at its lower end downwardly 100 into the upper end of the suspension tube 1 is a staff 14, the upper end of which projects above the level of the lifting propellers and carries an umbrella-shaped parachute 15, the folding ribs of which are attached to cables or cords 16 leading down into the space between the staff and wall of the tube 1 and connected with a collar or sleeve 17 slidably embracing the lower end of the staff. Connected with said sleeve is a rope 105 or cord 18, leading downwardly through the suspension tube to the car or basket 2 and 110

adapted to be engaged with a suitable holder 19, whereby the cords 16 may be drawn down to fold the parachute and maintain it in folded position. If at any time the machine should become inoperative from the failure of the motor or damage to the propellers, or either cause, the pilot by releasing the controlling rope may free the parachute, allowing it to spread open and fill 10 with air to secure the safe descent of the machine to the ground.

It will be observed that the car is arranged below the supporting surfaces so that the weight will be placed at such a low point 15 that the center of gravity of the machine will be beneath the supporting surfaces, whereby the car and lower portion of the suspension tube are adapted to serve the function of a gravity controlling element 20 for automatically maintaining the machine in a balanced or normal flying position.

Having thus described the invention, I claim:

1. A flying machine comprising an upright suspension tube, a car mounted upon the lower end of said tube, a frame structure mounted upon said tube above the car and below the upper end of the tube, a driving propeller mounted upon the tube within 25 the inclosure formed by said frame structure, and horizontal and vertical rudders at the front and rear of the frame structure, a pair of upright shafts mounted upon the upper portion of the frame structure, horizontally disposed lifting propellers mounted 30 upon said upright shafts on opposite sides of the upper end of the suspension tube, a motor upon the car, gearing for driving the propellers from the motor, a staff arranged 35 above the lifting propellers and having its lower end fitted within the upper end of the suspension tube, a parachute carried by said staff, and controlling means connected with the parachute and extending through the 40 suspension tube to the car for normally holding the parachute closed and releasing it to permit it to open and fill.

2. A flying machine comprising a vertical suspension tube, frame structures of substantially triangular form in plan and side 45

elevation arranged on opposite sides of and secured to said tube between its upper and lower ends, said frame structures being connected with each other, a car mounted upon the lower end of the tube, front and rear 55 horizontal and vertical rudders jointly supported by the frame structures, vertical shafts upon said frame structures, oppositely rotatable horizontal lifting wheels upon said shafts at opposite sides of the upper end of the suspension tube, a driving propeller supported by the suspension tube within the space inclosed by the frame structures, a motor on the car, gearing for driving the propellers from said motor, a staff 60 arranged above the lifting wheels and having its lower end fitted within the upper end of the suspension tube, a parachute supported by said staff, a sleeve slidably mounted upon the shaft within the suspension tube, 70 cords connecting said sleeve with the parachute, and a holding and releasing cord connected with the sleeve and extending downwardly through the suspension tube into the car.

3. In a flying machine, a framework, a suspension tube carrying the framework and extending above and below the same, a car supported upon the lower end of said suspension tube, propelling means upon the 75 framework, oppositely rotating lifting wheels at the top of the framework on opposite sides of the longitudinal center thereof, a staff entering the upper end of the tube, and projecting upwardly between and above 80 said lifting wheels, a folding parachute carried by said staff, a sleeve slidably engaging the staff within the suspension tube, cords connecting the parachute with said sleeve, a controlling cord connected with the sleeve and extending downwardly through the suspension tube, and means with which the said cord is adapted to be engaged to hold the 85 parachute normally collapsed.

In testimony whereof I affix my signature, 90 in presence of two witnesses.

JESSE J. DILLON.
